UNITED STATES PATENT OFFICE.

MATTHEW J. DUNFEY, OF WATERTOWN, MASSACHUSETTS, ASSIGNOR TO WM. FILENE'S SONS COMPANY, OF BOSTON, MASSACHUSETTS, A CORPORATION OF MASSACHUSETTS.

TICKET-CLIPPING MACHINE.

Application filed March 10, 1924. Serial No. 698,182.

In department stores and other large mercantile establishments it is customary to provide goods with tickets having duplicate portions, one portion being cut off and retained when the article is sold. The retained portion of the ticket serves to maintain an automatic inventory and is also useful for reference when an article is returned for credit or exchange. Heretofore, it has been customary to clip the tickets with a pair of shears which has led to a number of difficulties. The clipped portions of the tickets frequently become lost, and in many cases the sales person fails to clip the ticket. In some cases the sales person acting in collusion with a customer would allow an article to be carried away without payment with a view to having the customer return the article at a later time for refund. Objects of the present invention are to provide a machine which will assist in maintaining an automatic inventory, in preventing thefts by sales persons acting in collusion with customers, and generally to expedite the sales management of department stores and the like.

In one aspect, the present invention comprises a clipping machine having means for depositing the clipped portion of the ticket in a locked box so that the sales person has no access thereto. In another aspect, the invention comprises a clipper having an irregular cutting edge, that is, a clipping edge other than straight for cutting the tickets with a distinctive contour which would be difficult to imitate with a pair of scissors.

According to the preferred method of operation, the wrapping or checking clerk will permit no article to be delivered to a customer unless the ticket on the article is clipped in the aforesaid distinctive manner, whereby no article can be delivered without payment. The refund clerk will make no refund unless the article returned bears a ticket cut in a distinctive manner peculiar to the particular store, so that no refunds will be made except in case of bona fide sales. Inasmuch as every ticket must be clipped before the article can be delivered, and inasmuch as each clipped ticket is automatically deposited in a locked box, the perpetual inventory may be maintained correctly.

For the purpose of illustrating the genus of the present invention, one concrete em-

bodiment is shown in the accompanying drawings, in which:

Fig. 1 is a front elevation of the machine;

Fig. 2 is a side elevation;

Fig. 3 is a section on line 3-3 of Fig. 1; 60

Fig. 4 is a section on the line 4-4 of Fig. 1; and

Fig. 5 is a diagram showing a modified contour for the cutter.

The particular embodiment of the invention chosen for the purpose of illustration comprises box B having in the front thereof a locked door D and in the top thereof a ticket receiving opening O. Mounted in front of the opening by means of screws A 70 is a stationary cutter S having a serrated cutting edge E. Extending upwardly from the rearward part of the top of the box is an integral bracket F having vertically spaced guides G in which a hand-operated plunger P reciprocates vertically, a spring H operating between the lower guide G and a collar I upon the plunger P normally to hold the plunger in its uppermost position shown in the figures. On the lower end of the plunger P is a cutter C having a serrated cutting edge complementary to the edge E on the stationary cutter S. A rod R sliding forwardly and rearwardly in the lower portion of the bracket F carries on its forward end 75 a stop T which limits the extent to which a ticket may be inserted between the cutters, the rod R being held in adjusted position by set-screw U.

In operation, the ticket is inserted into the front of the box between the two cutters until the end of the ticket engages the stop T, whereupon the plunger P is given a sharp blow to clip the ticket. The clipped portion of the ticket falls through opening 90 O into the box B and inasmuch as the opening O is substantially closed when the plunger is depressed, it is impossible for the sales person to prevent the clipped ticket from being deposited in the box. 95

Instead of a serrated edge of the character shown in Fig. 4, the cutter may be provided with any irregular but distinctive cutting edge as, for example, an edge adapted to produce a cut such as shown at K in 105 Fig. 5.

I claim:

1. A machine for clipping tickets comprising a box having a ticket receiving opening, a cutting edge on one side of the open- 110

ing, a ticket stop on the opposite side of the opening, said stop being adjustable toward and from said edge, and a cutter movable between said edge and stop to clip a ticket 5 and deposit the clipped portion through said opening into the box.

2. A machine for clipping tickets having a ticket opening, an irregular cutting edge on one side of the opening, a ticket stop 10 spaced from said edge, and an irregular cutter complementary to said edge movable between the edge and stop to clip a ticket at a predetermined distance from the end engaging said stop, whereby tickets carrying two sets of indicia may be distinctively 15 cut intermediate the two sets.

3. A machine for clipping tickets carrying two sets of indicia comprising a stationary cutter having an irregular cutting 20 edge and a movable cutter having a complementary cutting edge, the space in the rear of the cutters being unobstructed a distance sufficient to permit the insertion of the part carrying one set of indicia, whereby tickets 25 may be cut in a distinctive manner between the two sets of indicia.

4. A machine for clipping tickets comprising a box having a ticket receiving opening at least substantially as wide as the 30 tickets, a pair of cutters disposed on opposite sides of a ticket positioned with one end overlapping said opening, the cutter on the opening side of the ticket being disposed

on the side of the opening from which the ticket is inserted and the other cutter being 35 opposite the opening and both cutters extending substantially the full width of the ticket, whereby the ticket may be cut from side to side and the forward end deposited in the box.

5. A machine for clipping tickets comprising a box having a ticket receiving opening at least substantially as wide as the ticket and beneath the end of a ticket inserted for clipping, upper and lower cutters extending from side to side of an inserted ticket, the upper cutter being opposite the opening and the lower cutter being disposed on the side of the opening from 45 which the ticket is inserted, the cutters having non-rectilinear cutting edges shaped to 50 cut the ticket along an outline difficult to imitate.

6. A machine for clipping tickets comprising a box having a ticket receiving opening at least substantially as wide as the ticket and approximately beneath the end of a ticket inserted for clipping, and cutters extending substantially the full width of an 55 inserted ticket on opposite sides of the 60 ticket, whereby an inserted ticket may be severed from side to side and the forward end automatically deposited in said box.

Signed by me at Boston, Massachusetts,
this 23rd day of February 1924.

MATTHEW J. DUNFEY.
